Primary Examiner—Martie Thompson**Attorney, Agent, or Firm—Norman B. Rainer****[57] CLAIM**

The ornamental design for a writing implement having dual distance-measuring rulings, as shown and described.

DESCRIPTION

FIG. 1 is a side view of a writing implement having dual distance-measuring rulings, showing my new design; FIG. 2 is a side view thereof, taken opposite to the side shown in FIG. 1;

FIG. 3 is a front view thereof, the opposite rear view being plain and unornamented;

FIG. 4 is a top view thereof; and,
 FIG. 5 is a bottom view thereof.
